UNITED STATES PATENT OFFICE

157,705

ELECTRIC RANGE BACKSPLASHER

Ray C. Sandin, Oak Park, Ill., assignor to Hot-point, Inc., a corporation of New York

Application May 6, 1949, Serial No. 2,508

Term of patent 14 years

(Cl. D81—25)

To all whom it may concern:

Be it known that I, Ray C. Sandin, a citizen of the United States, residing at Oak Park, in the county of Cook and State of Illinois, have invented a new, original, and ornamental Design for an Electric Range Backsplasher, of which the following is a specification, reference being had to the accompanying drawing, forming a part thereof.

In the drawing, the figure is a front perspective view of an electric range backsplasher, showing my new design.

I claim:

The ornamental design for an electric range backsplasher, as shown.

RAY C. SANDIN.
